CATHODE RAY TUBE SUPPORT

Albert Blain, Philadelphia, Pa., assignor to Radio Corporation of America, a corporation of Delaware

Application June 30, 1937, Serial No. 151,134

3 Claims. (Cl. 250—141)

My invention relates to electrical apparatus of the type employing cathode ray tubes, and particularly to means for supporting a cathode ray tube.

5 In apparatus of the above-mentioned type, such as television receivers and cathode ray oscilloscopes, it is desirable to have an inexpensive structure which will hold the cathode ray tube securely in position and which is so designed that the tube may be removed easily from the apparatus. If deflecting coils are employed for deflecting the cathode ray, the problem of obtaining a suitable cathode ray tube mounting is complicated by the fact that the deflecting coil 10 unit or deflecting yoke surrounds the tube.

Since the preferred deflecting yoke is a solid cylindrical structure, the tube must be moved endways into it. A split yoke would overcome this difficulty, but such yokes are objectionable 20 from the manufacturing standpoint.

It is, accordingly, an object of my invention to provide an improved supporting structure for cathode ray tubes.

It is a further object of my invention to provide an improved mounting for cathode ray tubes having deflecting coils.

It is a still further object of my invention to provide an improved cathode ray tube and deflecting coil assembly for television receivers, cathode ray oscilloscopes, or the like.

35 In a preferred embodiment of my invention, a deflecting yoke is mounted on the chassis of the television receiver or the like and opposite an opening in the front panel of the apparatus, this opening being large enough to admit the large end of the cathode ray tube. A plurality of spring members are so mounted around the periphery of this opening that when the cathode ray tube is moved into position from the front 40 of the apparatus, the spring members engage the periphery of the large end of the tube and hold it in position.

The invention will be better understood from the following description taken in connection 45 with the accompanying drawings in which

Figure 1 is a side view, partly in section, of a portion of a television receiver embodying my invention.

Figure 2 is a front view of the supporting spring structure employed in the receiver shown in Fig. 50 1, and

Figure 3 is a view taken in cross-section on the line 3—3 in Fig. 1.

Referring to Fig. 1, there is illustrated a portion 55 of a television receiver in which a cathode

ray tube 10 is mounted horizontally. The receiver includes a cabinet having a front panel 11. A television chassis, indicated at 12, is supported inside the cabinet, most of the chassis elements being omitted from the drawings in order to simplify it.

The cathode ray tube 10 is of a well-known type comprising an evacuated envelope, one portion of which is cylindrical and of comparatively small diameter and the other portion of which 10 is conical in shape and of comparatively large diameter at the extreme end.

In the receiver illustrated, the cathode ray is deflected by means of a deflecting coil unit or yoke indicated at 13. The yoke may be of any 15 suitable construction but, preferably, is of the type described and claimed in application Serial No. 66,171, filed February 28, 1936, in the name of William A. Tolson, and assigned to the Radio Corporation of America. The deflecting yoke 20 illustrated is of this type. It is in the form of a cylinder having an opening of slightly larger diameter than the diameter of the cylindrical portion of the tube 10 whereby it may be slipped over the small end of the tube.

25 The yoke 13 is supported in a bracket 14 extending from the chassis 12.

The cabinet panel 11 has an opening 16 therein which is large enough to receive the large end of the tube 10. A removable bezel 17 fits over 30 the end of the tube and is supported in a manner which is described hereinafter.

Referring now to the spring-supporting structure for the cathode ray tube, as shown in Figs. 1 and 2, it comprises a plurality of springs 18 35 which engage the front edge of the tube 10 and a plurality of springs 19 which engage the conical portion of the tube near the front end thereof. The springs 18 and 19 are located alternately around the periphery of the opening 10 and are 40 riveted or otherwise suitably fastened to a supporting ring 21 attached to the panel 11.

It will be seen from an inspection of Fig. 1 that, with the bezel 17 removed, the tube 10 may be moved into position in the receiver from the front side thereof. When placing the tube in the receiver, the small end of the tube is guided through the deflecting yoke 13. As the conical surface of the tube engages the springs 18 they are moved outwardly and finally slide over the front edge of the tube. The conical surface is now in engagement with the springs 19. Since the springs 18 tend to move the tube in one direction, while the springs 19 tend to move it in the opposite direction, the front end of the tube is 50 55

held firmly in a centralized position. The other end of the tube is, of course, supported by the yoke 18.

When a cathode ray tube is supported as described above, the tube socket which engages the contact pins at the small end of the tube (not shown) usually is attached to the end of a flexible cable since the socket does not need to function as part of the tube support.

10 After the tube 10 has been mounted in the receiver, the bezel 17 is attached. This is done by holding the bezel in position and rotating it a few degrees as will be understood from the description which follows.

15 Referring to Figs. 1 and 3, the bezel 17 has a bolt or stud 22 projecting therefrom. A similar bolt or stud (not shown) is attached to the bezel at a diametrically opposite point.

As shown in Fig. 2, the ring 21 has two keyhole-shaped openings 24 and 26 therein at diametrically opposite points. These openings are large enough at one end at least to permit the entrance of the heads of the studs projecting from the bezel. Fastened to the back of the ring 21 there 25 are slotted springs 27 and 28, the slots of these springs being positioned over the openings 24 and 26 and being narrower than the heads of the two studs projecting from the bezel 17.

It will be seen that the back end of each slot 30 is enlarged slightly as indicated at 25 and 30. By giving the narrower part of each slot a width just slightly less than the small diameter of the stud 22, the action of the studs as the bezel is rotated into place is to spread the springs slightly 35 whereby the studs snap into place at the rear of the slots as the bezel is rotated into position.

Thus, it will be seen that the bezel may be fastened in position by putting the bezel studs through the openings 24 and 26 and then rotating the bezel clockwise whereby the stud heads ride up onto the springs 27 and 28, the studs finally snapping into place at 25 and 30.

From the foregoing description, it will be seen that I have provided a cathode ray tube mounting or assembly which is adapted for economical manufacture in large quantities and which permits easy and rapid replacement of the cathode ray tube.

I claim as my invention:

50 1. Cathode ray tube apparatus comprising a cabinet in which is to be mounted a cathode ray tube of the type comprising an evacuated envelope which is enlarged at one end whereby said envelope has a point of maximum diameter and has a smaller diameter on each side of said point and which is of comparatively small diameter at the other end, said cabinet having a front panel, said panel having an opening therein large enough to admit the enlarged end of said tube, a plurality of springs located around said opening and so mounted on said panel as to engage the enlarged portion of said envelope on one side of said

point, and a plurality of springs located around said opening and so mounted on said panel as to engage the enlarged portion of said envelope on the opposite side of said point whereby said tube may be moved into said cabinet from the front side thereof into a position where said springs grip said enlarged portion to hold it securely in position. 5

2. Cathode ray tube apparatus comprising a cabinet in which is to be mounted a cathode ray tube of the type comprising an evacuated envelope which is enlarged at one end whereby said envelope has a point of maximum diameter and has a smaller diameter on each side of said point and which is of comparatively small diameter at the other end, said cabinet having a front panel, said panel having an opening therein large enough to admit the enlarged end of said tube, a plurality of springs located around said opening and so mounted on said panel as to engage the enlarged portion of said envelope on one side of said point, a plurality of springs located around said opening and so mounted on said panel as to engage the enlarged portion of said envelope on the opposite side of said point, and a deflecting coil yoke mounted in said cabinet with an opening therein in line with the opening in said panel whereby said tube may be moved into said cabinet from the front side thereof into position where the small end of said tube passes through said yoke and where said springs grip said enlarged portion to hold it securely in position. 10

3. Cathode ray tube apparatus comprising a cabinet in which is to be mounted a cathode ray tube of the type comprising an evacuated envelope which is enlarged at one end whereby said envelope has a point of maximum diameter and has a smaller diameter on each side of said point and which is of comparatively small diameter at the other end, said cabinet having a front panel, said panel having an opening therein large enough to admit the enlarged end of said tube, a supporting ring, a plurality of springs located around said opening and so mounted on said supporting ring as to engage the enlarged portion of said envelope on one side of said point, a plurality of springs located around said opening and so mounted on said supporting ring as to engage the enlarged portion of said envelope on the opposite side of said point, and a deflecting coil yoke mounted in said cabinet with an opening therein in line with the opening in said panel whereby said tube may be moved into said cabinet from the front side thereof into position where the small end of said tube passes through said yoke and where said springs grip said enlarged portion to hold it securely in position, and a bezel for said front panel opening, said bezel having supporting studs projecting therefrom, and means on said supporting ring for engaging the ends of said studs to hold said bezel in position. 15

ALBERT BLAIN.
